IMPROVED STARTING PUMP MECHANISM.

HERMANN LEMP, OF LYNN, MASSACHUSETTS, ASSIGNED TO GERMANY ENGINEERING COMPANY, A CORPORATION OF NEW YORK.

PUMP FOR SUPPLYING FUEL TO INTERNAL-COMBUSTION ENGINES.

1,076,502.

Specification of Letters Patent.

Patented Oct. 21, 1913.

Application filed February 26, 1912. Serial No. 676,774.

To all whom it may concern:

Be it known that I, HERMANN LEMP, a citizen of the United States, residing at Lynn, county of Essex, State of Massachusetts, have invented certain new and useful Improvements in Pumps for Supplying Fuel to Internal-Combustion Engines, of which the following is a specification.

The present invention relates to pumps for supplying fuel to internal combustion engines and more especially to that type of engine wherein the action of the piston causes a sufficiently high temperature of the air compressed in the cylinder to fire the fuel charge when it is admitted under the control of a suitable valve, the fuel being commonly introduced into the cylinder space by compressed air, the pressure of which is greater than that of the compression pressure.

The object of my invention is to improve the construction and the reliability of operation of such pumps.

For consideration of what I believe to be novel and my invention, attention is directed to the accompanying description and claims appended thereto.

In the accompanying drawings which illustrate one of the embodiments of my invention, Figure 1 is a partial view in elevation of an internal combustion engine fitted with my improved pump mechanism; Fig. 2 is a detail view illustrating the means for adjusting the fulcrum of the pump lever; Fig. 3 is a view partially in section and partially in elevation of a displacement pump; Fig. 4 is a section taken on the line 4—4 of Fig. 3; Fig. 5 is a section on an enlarged scale through the fulcrum means of the pump levers; Fig. 6 is a detail view of a sliding block which carries the fulcrum of the pump actuating lever; Fig. 7 is a detail view of a governor actuated slide, and Fig. 8 is a diagram illustrating the operation of the pump.

1 indicates the head of the cylinder of an internal combustion engine. The engine may have one or more cylinders as desired.

In the present instance it is supposed to have four.

2 indicates an upright shaft that is driven

by the main shaft of the engine. On the upper end of the shaft is a speed governor 3 of any suitable construction. It is provided with a sliding collar 4 that is moved by the weights of a speed governor in accordance with changes in speed of the engine. This collar is arranged to move the governor lever 5 about its fixed pivot 6.

Mounted on the shaft 2 is a gear 7 shown in dotted lines which meshes with a gear 8 also shown in dotted lines. These gears are inclosed in a suitable housing 9. The gear 8 is mounted on the shaft 10 which actuates the valves of the engine through suitable means such as cams and levers in the ordinary manner. The shaft is carried by brackets 11 bolted to the side of the engine. On the end of the cam shaft is an eccentric 12 that is surrounded by an eccentric strap 13 which is connected to the eccentric rod 13. The lower end of the eccentric rod is attached to one end of the pump actuating lever 14. The other end of this lever is connected by links 15 to the pump cross-head 16, the lever being provided with a fulcrum 17 which is mounted in two sliding blocks 18, said blocks being located on opposite sides of the lever 14 so as to equalize the strains. The blocks 18 are located between vertically extending guides 19 which are formed in the downwardly extending members 20 of a casting 21 which is secured to one of the brackets 11.

22 indicates a governor actuated slide that is arranged to move to and fro under the control of the speed governor. To this end, links 23 and 24 are provided that are pivotally connected on their right-hand ends to the slide and on their left-hand ends to the arms 25 and 26. The reason for employing two of these arms is to cause simultaneous and corresponding movements of the governor actuated slides 22. The arms are carried by a spindle 27 to which is attached the lever 28. The free end of this lever is connected by an adjustable rod 29 with the governor actuated lever 5.

Each of the governor actuated slides is rectangular in shape and is guided in its movements by suitable guides formed in the members 20 and in the plate 30 connecting

the members as best shown in Fig. 5. The slide is also provided with a diagonally arranged recess 31, the upper and lower surfaces of which are shaped to receive the fulcrum adjusting and carrying block 18. It is to be noted that the block is capable of moving vertically within the guides 19, and that the motion of the governor actuated slide is at right angles to that of the block. 10 Owing to the diagonal recess in the slide it follows that as the slide is moved from the position shown in Fig. 1 toward the left that the block will be raised and in so doing, change the position of the fulcrum 17 of 15 the governor actuated lever 14. Since the eccentric rod 13 has an unvarying length of stroke, it follows that as the position of the fulcrum 17 is changed that the region of reciprocation of the cross-head 16 will 20 change, the effect of which is to vary the effective discharge of the pumps actuated by the cross-head.

Referring to Figs. 3 and 4, the construction of the pump will be described. 16 indicates the cross-head which is connected to the governor actuated lever by the links 15. Actuated by the cross-head are as many pump plungers 32 as there are cylinders to the engine. Since each of these pumps is 30 of the same construction, a description of one of them will be sufficient. 33 indicates a fuel containing tank and located therein is a cylinder 34 having an enlarged head 35 which is seated in the tubular projection 36 formed on the underside of the tank, said cylinder being held in place by the nut 37. Formed in the side walls of the pump are one or more ports 38, four being shown in the illustration through which oil enters 40 the cylinder from the tank when the plunger 32 is in the raised position. As shown, the plunger is at the limit of its downward stroke. Surrounding the cylinder is a coiled compression spring 39 that tends at all times 45 to raise the plunger. The spring engages the nut 37 at the bottom and a collar 40 on the plunger at the top. By reason of the construction just described, I am able to do away with suction valves and at the same time insure a proper supply of fuel to the 50 pump cylinders at all times. 41 indicates a discharge valve which is normally held against its seat by the compression spring 42, that is contained in the screw-threaded 55 plug 43. 44 indicates a pipe for conveying fuel from the cylinder to one of the engine cylinders, it being understood that each pump is similarly provided with a discharge pipe. In order to guide the movements of 60 the cross-head 16, rods 45 are provided that enter tubular members or posts 46 that are open at their lower ends and are also screw-threaded to the base of the tank. In order

to insure a constant head of oil in the tank, a float 47 is provided that is located in the 65 float chamber 48 which is in open communication with the tank. This float is suitably guided in its vertical movements by a rod 49. Situated above the rod is a ball valve 50 that opens toward the float chamber and 70 permits oil to enter the chamber from the pipe 51 when it is open. When the valve is raised as shown in the drawing, the supply of fuel from the pipe 51 is cut off.

When the parts are in the position shown 75 in Fig. 1, the pump plungers are working with maximum effect; that is to say, each pump is delivering a full supply of fuel because the fulcrum 17 of the pump lever is at its lowest point. If now the speed of 80 the engine increases the governor will move the free end of the lever 5 upward, and in so doing cause the arms 25, 26 and links 23, 24 to move the slides 22 to the left, thereby raising the fulcrum adjusting and carrying plug 18. Since the eccentric rod 13 has a constant length of stroke and since the fulcrum 17 has been raised, it follows that the pump plungers while having the same length of stroke will be vibrating or moving 90 in a higher region than before and hence do not extend as far into the cylinders as before which means that less fuel will be discharged on each pump stroke. Each time a pump plunger uncovers its ports 38 fuel 95 will flow into the cylinder and it is evident that if the plunger does not descend to the same low point shown in Fig. 4 less fuel will be forced through the spring pressed discharge valve 41.

From the foregoing it will be seen that the pumps have a constant region of reciprocation and that their effective delivery changes with changes in position of the fulcrum 17 as determined by governor 105 actuated slide. Assuming an intermediate position of the fulcrum 17 and an increase in load on the engine causing a decrease in speed of the governor actuated lever 5 acting through the 110 arms 25, 26 and links 23, 24 will move the governor actuated slides 22 to the right, thereby lowering the position of the fulcrum 17 and increasing the effective delivery of 115 the pumps until the amount of fuel discharged to the engine balances the load.

The structure described has the advantage of being simple and rugged requiring only ordinary machine work and avoiding the use of especially well fitted parts.

In accordance with the provisions of the patent statutes, I have described the principle of operation of my invention, together with the apparatus which I now consider to represent the best embodiment 125 thereof; but I desire to have it understood

that the apparatus shown is only illustrative, and that the invention can be carried out by other means.

What I claim as new and desire to secure 5 by Letters Patent of the United States, is:

1. An internal combustion engine in combination with a displacement pump for supplying fuel thereto comprising a working cylinder, a port therein through which fuel 10 enters it, a discharge valve, a plunger in the cylinder which covers and uncovers the port, a vibratory lever which is pivotally attached to the plunger for actuating it, means for imparting a stroke of constant 15 length in an unvarying region to one end of the lever, a fulcrum for the lever in fixed relation thereto, and a governor driven by the engine for changing the position of the fulcrum to cause the plunger to vary its 20 travel with respect to the inlet port.

2. An internal combustion engine in combination with a pump for supplying fuel thereto comprising a working cylinder, an inlet port in the side of the cylinder, a 25 discharge valve, a plunger reciprocating in the cylinder which has a constant length of stroke but variable region of operation and covers and uncovers the port, a lever connected to the plunger, a fulcrum for the 30 lever in fixed relation thereto, a means carrying the fulcrum, and a governor driven by the engine for changing the position of the means in accordance with the load on the engine to change the region of reciprocation of the plunger with respect to the 35 inlet port.

3. An internal combustion engine in combination with a pump for supplying fuel thereto, comprising a working cylinder with 40 an inlet port in the side of the cylinder, a discharge valve, a plunger reciprocating in the cylinder which has a constant length of stroke but variable region of operation, a lever pivotally connected at one end to the 45 plunger, a driving means for imparting a vibratory movement to the lever of constant amount in a fixed region, a fulcrum for the lever, a sliding block that carries the fulcrum, a guide for the block, and a governor 50 driven by the engine for changing the position of the block to change the region of vibration of the plunger with respect to the inlet port.

4. An internal combustion engine in combination with a pump for supplying fuel thereto, comprising a working cylinder, an inlet port in the side of the cylinder, a discharge valve, a plunger reciprocating in the cylinder which has a constant length of 55 stroke but variable region of operation, a lever connected to the plunger for actuating it, a fulcrum for the lever, a sliding block which carries the fulcrum, means for hold-

ing the block against lateral movement, a slide which carries the block and moves it 60 in said means, and a governor driven by the engine for adjusting the slide longitudinally.

5. An internal combustion engine in combination with a pump for supplying fuel 70 thereto comprising a cylinder and a plunger reciprocating therein which has a constant length of stroke but variable region of operation, a lever connected to the plunger for actuating it, a fulcrum for the lever, a sliding block which carries the fulcrum, a slide which moves in a direction perpendicular to the direction of movement of the block and carries the same, and a governor driven by the engine for reciprocating the slide. 80

6. An internal combustion engine, in combination with a pump comprising a cylinder and a reciprocating plunger therein having an unvariable length of stroke, a lever connected to the plunger, a driving means for 85 the lever having a constant length of stroke, a fulcrum for the lever, a sliding block which carries the fulcrum, a guide for the block, a slotted slide in which the block is located, a guide for the slide that is perpendicular to that of the block, and means for reciprocating the slide to vary the region of reciprocation of the plunger. 90

7. An internal combustion engine, in combination with a pump comprising a cylinder 95 and a reciprocating plunger therein having an unvariable length of stroke, a lever connected to the plunger, a driving means for the lever having a constant length of stroke, a fulcrum for the lever, a pair of sliding blocks which carry the fulcrum, guides therefor, a pair of slides having slots therein in which the blocks are held, means for simultaneously moving the slides to adjust the position of the fulcrum, and a speed 105 governor driven by the engine which is connected to said means. 100

8. An internal combustion engine, in combination with a pump comprising a cylinder and a reciprocating plunger therein having 110 an unvariable length of stroke, a lever connected to the plunger, a driving means for the lever having a constant length of stroke, a fulcrum for the lever, a sliding block which carries the fulcrum, a hanger through 115 which the lever extends, a block that carries the fulcrum and is guided by the hanger, a slotted slide carrying the block which is supported and guided by the hanger and to which the thrust on the fulcrum is transmitted, a lever for reciprocating the slide, and a speed governor driven by the engine that is connected to the last named lever for moving it. 120

9. An internal combustion engine, in combination with a pump comprising a cylinder 125

having an inlet port in its wall, a plunger that reciprocates within the cylinder, covers and uncovers the port and has a constant length of stroke but variable region of operation, a discharge valve, a pump actuating lever, a means for vibrating the lever over a constant arc length but variable region, a fulcrum for the lever, and means for varying the position of the fulcrum to

change the effective delivery of the pump by 10 changing the distance that it overtravels the inlet port.

In witness whereof, I have hereunto set my hand this 8th day of February, 1912.

HERMANN LEMP.
